COVERED SERVING DISH

Frank D. O'Neill, 94 Wilcocks St. W.,
Toronto, Ontario, Canada

Filed Aug. 20, 1968, Ser. No. 13,201

Term of patent 14 years

Int. Cl. D7—99

U.S. Cl. D44—10

FIG. 1

FIG. 2

FIG. 3

FIG. 4

FIG. 5

FIG. 6

FIG. 1 is a perspective view of a covered serving dish showing my new design in a closed condition;

FIG. 2 is a perspective view from the opposite end, in open condition;

FIG. 3 is a reduced scale top plan view, in closed condition;

FIG. 4 is a reduced scale bottom plan view, in closed condition;

FIG. 5 is an elevational view from the right of FIG. 1; and

FIG. 6 is an end elevational view of FIG. 1.

I claim:

The ornamental design for a covered serving dish, as shown.
